UNITED STATES PATENT OFFICE.

MOORE GOODFELLOW, OF SPRINGFIELD, OHIO, ASSIGNOR OF ONE-HALF TO J. O. DYE, OF SPRINGFIELD, OHIO.

BEET-HARVESTER.

No. 860,655.

Specification of Letters Patent.

Patented July 23, 1907.

Application filed May 28, 1901. Serial No. 62,332.

To all whom it may concern:

Be it known that I, MOORE GOODFELLOW, a citizen of the United States, residing at Springfield, in the county of Clark and State of Ohio, have invented certain new and useful Improvements in a Beet-Harvester, of which the following is a specification.

My invention relates to beet harvesters, and more particularly to pulling devices for such machines.

The object of the invention is to provide a puller for an apparatus of this character which will effectually remove the beets from the ground, pull them vertically without dragging them through the ground and will further elevate the beets in a vertical direction until they come within the range of the elevating devices.

With these objects in view my invention consists of the construction hereinafter to be described, and then more fully pointed out in the claims.

In the accompanying drawings, Figure 1 is a top plan view of a machine embodying my pullers, with the elevating devices removed; Fig. 2 is a side elevation of such a machine; and Fig. 3 is a detail view of one of the pullers.

In these drawings, the reference letter *a* represents the ground wheels mounted upon the shaft *a'*, which, in turn, is carried by the frame *b* and has pivoted thereto the auxiliary frame *c*, in which are journaled the downwardly and forwardly extending shafts *c'*, supported near their lower ends in the frame or bracket *c'*, and provided at their upper ends with bevel gears 1, meshing with bevel gears *c*² on the shaft *c*² which is driven through the pinion *c*⁴ mounted thereon and the gear *a*⁴ mounted on the shaft *a'*.

Mounted on the lower ends of the shafts *c'* are the pullers *e* consisting of two downwardly and forwardly inclined revolving cones. These cones are arranged, of course, with their apexes directed forward and are provided with means for rotating them in opposite directions as above described, so that the adjacent sides of said cones, considering their lower portion as a starting point, rotate upwardly and inwardly towards each other. Each cone is provided with a plurality of spiral ribs 2, the ribs on the two cones being reversely arranged, and said ribs being so constructed that they gradually increase in size from the apex or base to the rear end of each cone, being therefore of minimum size at the front end and greatest at the rear end. As will be seen from Fig. 3 these ribs are so arranged that each of them, as the cone is revolving, will, when it comes into lifting position, be in a substantially horizontal plane. By reason of this construction I am enabled to obtain a direct lifting action in pulling the beet from the soil without crowding the beet forward. Moreover,

I have found in practice, that the spiral ribbed construction of the pulling cone passes more readily through the soil and is practically self-cleaning.

From the foregoing description, the operation of the device will be obvious. The pulling cones *e* are arranged at a proper angle to the ground by the adjustment of the auxiliary frame *c* around its pivotal connection on the shaft *a'* and are revolved in an inward and upward direction by means of the shafts *c'* and the bevel gearing connecting the same to the shaft *c*². As the machine moves forward the apexes of the cones move through the ground on the opposite sides of the row of beets, and, as the cone comes into contact with the sides of the beet, the spiral ribs on the cone take hold of the beet and raise the same from the ground, the cones passing alongside of the beet and retaining their hold thereon by means of the gradually decreasing distance between the ribs on the two cones, thereby lifting the beet vertically without crowding the same forward through the ground. As the beet reaches the rear of the cone and consequently its uppermost position, it comes into engagement with the lifting devices and is carried to the delivery conveyer.

Having thus fully described my invention, what I claim as new and desire to secure by Letters Patent, is:—

1. In a beet harvester, a pair of oppositely rotating cone-shaped pullers having spiral ribs thereon, the spiral ribs of one of said pullers being wound in a direction opposite to that in which the ribs of the other puller are wound, substantially as described.

2. In a beet harvester, a pair of oppositely rotating cone-shaped pullers having spiral ribs starting from the apex and gradually enlarging with the cones, the spiral ribs of one of said pullers being wound in a direction opposite to that in which the ribs of the other puller are wound, substantially as described.

3. In a beet harvester, a pair of oppositely rotating cone-shaped pullers having spiral ribs starting from the apex gradually enlarging with the cones and extending to their bases, the spiral ribs of one of said pullers being wound in a direction opposite to that in which the ribs of the other puller are wound, substantially as described.

4. In a beet harvester, cone-shaped pullers arranged with their axes inclined downward and forward and spiral ribs formed thereon, which, on their lifting sides, extend substantially in a horizontal plane, the spiral ribs of one of said pullers being wound in a direction opposite to that in which the ribs of the other puller are wound, substantially as described.

In testimony whereof, I have hereunto set my hand this 16th day of May A. D. 1901.

MOORE GOODFELLOW.
